US00D817993S

(12) **United States Design Patent** (10) **Patent No.:** **US D817,993 S**
(45) **Date of Patent:** **** May 15, 2018**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, San Jose, CA (US); **Chun Kin Minor Wong**, Cupertino, CA (US)

(73) Assignee: **Apple Inc.**, Cupertino, CA (US)

(**) Term: **15 Years**

(21) Appl. No.: **29/582,317**

(22) Filed: **Oct. 27, 2016**

(51) **LOC (11) Cl.** **14-04**

(52) **U.S. Cl.**

USPC **D14/487**; D14/490; D14/492

(58) **Field of Classification Search**

USPC D14/485-495

CPC ... B60K 37/00; G06F 3/0481; G06F 3/04845; G06F 3/04817; G06F 17/212; G06F 19/3406; G06T 13/80; G06T 15/02

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines represent a display screen or portion thereof, and form no part of the claimed design.

**1 Claim, 1 Drawing Sheet
